ATTORNEY

UNITED STATES PATENT OFFICE.

JAMES WILLIAM ALLEN, OF EUREKA SPRINGS, ARKANSAS.

COMBINED EVAPORATOR, BAKER, AND VENTILATOR FOR COOKING-STOVES.

SPECIFICATION forming part of Letters Patent No. 439,990, dated November 4, 1890.

Application filed July 1, 1890. Serial No. 357,449. (No model.)

To all whom it may concern:

Be it known that I, JAMES WILLIAM ALLEN, residing at Eureka Springs, in the county of Carroll and State of Arkansas, have invented 5 a new and useful Combined Evaporator, Baker, and Ventilator for Cooking-Stoves, of which the following is a specification.

My invention has for its object to provide a suitable ventilating device formed of a box 10 or drum adapted to be set over the stove and connected with the chimney-flue by suitable piping, which will serve to carry off the odors of cooking and be also adapted for use as an evaporator. It has also for its object to combine with such attachment a portable baking- 15 oven, adapted to be set on the stove and inclosed in said ventilating and evaporating box.

My invention consists in the sundry novel arrangement and peculiar combination of 20 parts, all of which will hereinafter be fully described in the annexed specification, and be particularly pointed out in the claims, reference being had to the accompanying drawings, in which—

25 Figure 1 is a perspective view of my improvement as applied for use. Fig. 2 is a longitudinal section thereof; and Fig. 3 is a transverse section on the line 3 3, Fig. 2.

In the accompanying drawings, in which 30 the same reference marks indicate like parts in all the figures, A denotes a cooking-stove of the ordinary construction, upon the top of which is supported my improved ventilating device, which consists of the box or drum B, 35 of a size sufficient to lap over the front and the ends of the stove-top, whereby air-inlets b b' are formed, and in which dampers b² are provided over the inlets b b', whereby said inlets may be closed when desired, a damper 40 b³ being also provided for the inlet b.

C indicates a series of telescopic pipe-sections joined with the upper end of the box B and connecting same with the chimney-flue, as shown. If desired, however, the pipes C 45 may be joined with the smoke-pipe c of the stove by any suitable connection, and thereby avoid the necessity of cutting another opening in the flue. I prefer, however, to arrange said pipes separate, as shown.

50 D indicates a damper arranged in the pipe C just above its connection with the box B.

The box B is formed with a series of ledges b⁵ b⁶, which serve as suitable supports for evaporating pans or frames, which can readily be slipped into position through a suitable 55 door E, hinged upon one end of the box, as shown.

It will be understood that the horizontal portion C' of the pipe C is held from movement and that the telescopic sections end below the upper joint C². To the section C³, I attach the ends of two ropes or chains F, which pass over pulleys f f and hang down within convenient reach of a person, suitable hand-holds or tassel being formed on the ends of 60 said ropes. By this arrangement it will be seen that when desired the operator by pulling upon the cords can raise the box up above the stove, (see dotted lines, Fig. 3,) so as to admit of ready access to the top of the same. 65 Any suitable means may be provided for holding the said device in its elevated position. 70

In connection with the above-described device I employ a baking-oven G, adapted to be placed upon the stove over the openings, and 75 which is formed with a series of divisions g g, so as to bake several tiers at one time. By this arrangement it will be seen that when the baking-oven is used that by letting down the box B over the same and closing the dampers 80 all the heat from the top of the stove is concentrated within said box, thereby baking in a much quicker time than usual. It will also readily appear that during ordinary cooking the box B may be let down over the several 85 pots, and thereby carry all the odors directly into the chimney-flue.

Having thus described my invention, what I claim, and desire to secure by Letters Patent, is—

1. A combined evaporator and ventilator for cooking-stoves, consisting of a box-like frame formed with an outlet in its upper end arranged to communicate with the chimney-flue, the front and ends formed with extensions arranged to overlap the edges of the stove, whereby air-inlets are formed, and dampers operating in said box, adapted to open or close said inlets, substantially as and for the purpose described. 95

2. In a combined ventilator and evaporator for cooking-stoves, the combination, with the 100

stove A, of the box B, formed on its lower front and end portions with outwardly-projecting flanges b, whereby air-inlets b' are formed, damper b², located in said box to regulate the draft through such openings, a series of ledges b², formed on the inside of the ends of said box B, a discharge-opening formed in the upper end of said box, and telescopic pipe-

connections between said opening and the chimney-flue, all arranged substantially as to and for the purposes described.

JAMES WILLIAM ALLEN.
